UNITED STATES PATENT OFFICE.

THOMAS G. HALL, OF BROOKLYN, ASSIGNOR TO ISAAC N. COOK AND SAMUEL B. McLANE, OF YONKERS, NEW YORK.

TOOL FOR GRASPING AND HOLDING ARTICLES.

SPECIFICATION forming part of Letters Patent No. 275,335, dated April 3, 1883.

Application filed November 29, 1882. (No model.)

To all whom it may concern:

Be it known that I, THOMAS G. HALL, a citizen of the United States, and a resident of Brooklyn, Kings county, New York, have invented certain new and useful Improvements in Tools for Grasping and Holding Articles, of which the following is a specification.

My invention relates mainly to an improvement on that class of vises and brace-wrenches which employ a tail-screw to spread the tails of the jaws; and it consists in arranging the tails of the jaws or portions thereof to engage and play in grooves or keyways in a fixed part, whereby torsion of the jaws is prevented, and in a direct pull longitudinally of the jaws the strain is taken wholly or partially off the screws.

In the drawings which serve to illustrate my invention, Figure 1 is a side view of a hand-vise provided with my improvements; and Fig. 2 is an edge view of the same, taken at right angles to Fig. 1. Fig. 3 is a view similar to Fig. 1, illustrating the application of my invention to a combined wrench and bit-brace; and Fig. 4 is an edge view of the tail portion of same as viewed from arrow 4 in Fig. 3. Figs. 5 and 6 illustrate modifications.

Referring to Figs. 1 and 2 most particularly, A A are the jaws of the hand-vise, a a being the heads of the jaws, and b b the tails of the same. B is a right-and-left screw, designed to set or adjust the heads of the jaws on the article to be held, and C is a right-and-left screw, adapted to spread the tails of the jaws and cause the heads to clamp the article forcibly, the jaws acting on the pivoted or rocking nuts c c of the screw B as on fulcrums. The tail-screw C is also provided with rocking nuts.

So far as above described, the tool is essentially old, having been shown in former patents of J. Goodrich, notably his Patent No. 227,686, of May 18, 1880. I find, however, that unless some provision is made to prevent it, there is a certain amount of distortion of the vise-jaws produced by necessary torsional strains brought upon them in use, and caused mainly by a certain looseness about the bearings of the tail-screw. This distortion is injurious to the vise, and to obviate it I provide the vise with the appliances I will now describe.

D is a block through which the tail-screw C passes, and in which it is rotatively mounted. To prevent the screw from playing endwise through or in this block, a circumferential groove is cut in the body of the screw where it rests in the block, and a set-screw, d, is screwed through the block until its point engages the groove in the screw. This device, which permits the screw to turn freely, is shown in the former patents of Goodrich.

Formed in one with or attached to the block D is a cross-piece, E, having tubular end portions, e e, longitudinally slotted or cut through at their upper sides, as is clearly shown in Fig. 65 2, where the cross-piece is shown in end elevation. The tail of each vise-jaw is provided with a cylindrical slide, f, which fits snugly into the tubular hollow in the cross-piece, its neck, which joins it to the tail of the jaw, 70 taking into and playing in the slot in the upper side of the tubular end portion, e. When the jaws are spread by means of the screws the slides f play in the tubular portions e of the cross-piece E, and, while they permit the 75 jaws to move freely toward or from each other, they prevent any torsional strain from distorting the jaws.

The vise shown in Figs. 1 and 2 is adapted particularly for use in putting up telegraph-wires, where the vise is clamped on the wire and the latter strained by means of a strap attached to the cross-piece E by means of an eye, g, in the latter. This longitudinal strain on the vise is very great, and where the slides f 80 are not employed said strain is thrown wholly upon the tail-screw C through the medium of the block D, as will be readily seen. These slides, however, take under overhanging parts of the tubular end portions, e, and thus take 90 the strain in whole or in part off the screw.

In adjusting the jaws to the article to be grasped they are usually spread by means of both screws B and C, so as to preserve approximately the parallelism of the jaws; but 95 when the article is properly placed in the jaws the tail-screw is turned until the jaws grasp the article firmly. This will spread the tails of the jaws ordinarily a little more than the heads and throw them out of parallelism. 100 So far as the screws are concerned, this is provided for by the employment of the rocking

nuts, and the slight looseness of the parts where the slides *f* fit in the tubular portions *e* will be sufficient to permit the jaws to stand at the necessary angle with each other. The 5 slide *f* might, however, be made spherical, as shown in the sectional view, Fig. 5, if desired, which would provide for all the divergence of the jaws that could possibly be needed, and yet permit the parts to fit snugly together.

10 Referring now to Figs. 3 and 4, wherein I have shown my improvements as applied to a combined wrench and bit-brace, the same letters of reference refer to the same parts generally, the only difference being that the block 15 *D* extends up to the screw *B* and the latter has a bearing therein, and the wrench is provided with guides *F* for the jaws. This construction is the same as that illustrated in Goodrich's patent before mentioned, and is 20 merely used here by way of illustration. I prefer, also, in this case, to make the slides *f* in the form of dovetails arranged to engage and slide in dovetail or undercut grooves in the cross-piece *E*. This cross-piece forms a 25 part of the brace, which I have not deemed it necessary to show in full, as it is or may be of the usual shape and construction.

In employing this tool as a wrench to grasp a nut, *G*, for example, there is considerable 30 twisting or torsional strain on the jaws, as will be readily seen, and this strain is resisted by the engagement of the slides *f* with the cross-piece *E*.

Where the tool is to be used mainly for boring, or for screwing on nuts arranged as 35 shown in Fig. 3—that is to say, where the axis of the bore in the nut is substantially parallel with the axis of the tool—it would be sufficient to merely form a groove in the cross-piece *E*, as shown in the modification, Fig 40 6, and to provide the jaw of the wrench with a plain slide to fit in said groove. This construction is the same as that shown in the other figures, except that the groove is not undercut; but 45 where the tool is to be employed for screwing on nuts arranged and grasped at right angles to that shown in Fig. 3—that is to say, with the axis of the bore of the nut at right angles to the axis of the tool—it is important that

the slides *f* should be arranged to take under 50 some part of the cross-piece *E*, because in this case the strain tends to draw one or the other of the said slides out of its groove, as will be understood.

In Figs. 1 and 3 I have shown parts of the 55 jaws of the tool broken away to illustrate the construction of the rocking nuts, although I make no claim to these. The screws *B* and *C* may be manipulated by means of winged nuts or milled disks, as shown.

Although I have shown my improvements as applied to a vise and wrench with rocking nuts, they are equally well adapted to any of the class of parallel vises—that is to say, to that class of vises wherein the tails of the 65 jaws are spread equally with their heads by any means whatever.

Having thus described my invention, I claim—

1. As a means for preventing torsion of the 70 jaws in a tool for grasping and holding articles, the block *D*, mounted on the tail-screw of the tool, and the cross-piece *E*, attached thereto and provided with grooves to receive projections on the tails of the jaws, substantially as set forth.

2. The combination, with a tool for grasping and holding articles, of the block *D*, mounted on the tail-screw of the tool, and the cross-piece *E*, provided with undercut grooves 80 to receive the slides on the tails of the jaws, all constructed and arranged to operate substantially as set forth.

3. The combination, in a vise, of the vise-jaws provided with cylindrical slides *f*, the 85 screws for spreading the jaws, the block *D*, mounted on the tail-screw of the vise, and the cross-piece *E*, attached to the block *D* and provided with slotted cylindrical cavities to engage the slides on the jaws, all arranged to 90 operate substantially as set forth.

In witness whereof I have hereunto signed my name in the presence of two subscribing witnesses.

THOMAS G. HALL.
